WILLIAM BRIGGS, OF NORRISTOWN, PENNSYLVANIA.

Letters Patent No. 88,605, dated April 6, 1869.

IMPROVEMENT IN BREECH-LOADING FIRE-ARMS.

The Schedule referred to in these Letters Patent and making part of the same.

To all whom it may concern:

Be it known that I, WILLIAM BRIGGS, of Norristown, State of Pennsylvania, have invented a combined breech and muzzle-loading fire-arm; and I do hereby declare the following to be a full, clear, and exact description of the same.

My invention relates to that class of fire-arms in which the barrels are caused to slide forward from the breech-piece, to open the breech; and

My invention consists in a peculiar arrangement of levers for operating the barrels.

In order to enable others skilled in the art to make and apply my invention, I will now proceed to describe its construction and operation, reference being had to the accompanying drawing, which forms a part of this specification, and in which—

Figure 1 is a sectional elevation of my combined breech and muzzle-loading fire-arm, showing a portion of the stock in red lines;

Figure 2, a section through one of the barrels, showing the breech open;

Figure 3, a transverse section on the line 1-2, fig. 1, looking toward the front of the breech-piece;

Figure 4, a transverse section on the line 3-4, fig. 1;

Figure 5, a plan view of fig. 2; and

Figure 6, an enlarged view of a portion of fig. 4.

Similar letters refer to similar parts throughout the several views.

A metal breech-piece, A, is secured, by the usual tongue, a, to the stock B of a double-barrelled fire-arm, and to the front portion of this breech-piece is screwed, or otherwise secured, a hollow stem, or tube, C.

D represent the barrels of the fire-arm, secured together in the ordinary manner, and having, at their under side, a rib, E, through which extends a longitudinal opening, b, for the admission of the tube C.

The barrels are thus arranged to slide toward or from the breech-piece A upon the tube C, the friction between them and the tube being reduced by straight or spiral grooves, c, cut in the edges of the opening, b, as shown in fig. 6.

The barrels are operated by an arm, F, the inner end of which turns upon a stationary pin, d, in the breech-piece, and by a lever, G, the inner end of which is hung to a pin, e, secured to projections f f on the rib E of the barrels, the arm and lever being connected together by a pin, g, as shown in figs. 1 and 2.

The upper edge of the arm F is curved, so that when the barrels are closed it may adapt itself to the curved shape of the projections f f of the rib E; and the arm is recessed, as shown at h, for the reception of a portion of the lever G. (See figs. 1 and 2.)

The whole weight of the barrels, in sliding upon the tube C, is not borne by the latter, which serves more as a guide, to maintain them in a proper position, than as a support, but by the front portion, B', of the stock, as shown in fig. 4, and the motion of the barrels is limi-

ited by the retaining-pin i of the stock, (shown in red lines, figs. 1 and 4,) which enters a longitudinal slot, j, formed in a projecting portion of the rib E of the barrels.

When the breech is closed, the arm F and lever G are flush with the under side of the stock, in which position they are maintained by a spring-catch, k, at the outer end of the lever.

The hooked end of this spring-catch passes through an opening in the rib E, and enters a notch formed for its reception, on the lower edge of the slot j, from which it may be withdrawn, when desired, by operating a ring, k', at its opposite end, (figs. 1 and 2.)

A steel cartridge-case, H, is arranged to fit snugly in an enlargement, m, of the bore of each barrel, the flange of the cartridge bearing against the rear end of the barrel, and its front end against the shoulder n in the bore.

The chamber p, in the cartridge-case, is of such a diameter as to form a continuation of the bore, and in the recessed rear end of the case is a nipple, q. (See fig. 2.)

In the breech-piece A, at a point directly in the rear of each of the barrels, is formed a circular recess, r, for the reception of the flange of the cartridge-case, and communicating with each of these openings, is a striker-pin, s, and beneath each opening a spring cartridge-extractor. (See figs. 2 and 3.)

The barrels, when closed, are maintained in a proper position in respect to the breech-piece A, and are prevented from turning laterally upon the tube C, as a centre, by means of a lug, v, on the tube, which enters a recess on the under side, and at the rear end of the rib E, (figs. 1 and 3.)

Operation.

When the above-described fire-arm is to be used as a breech-loader, a number of the cartridge-cases is prepared, each being loaded with ordinary ammunition, and properly capped.

The breech having been opened, as shown in fig. 2, one of these loaded cases is inserted into the enlarged rear of the bore of each barrel, after which the lever G is pushed forward in the direction of its arrow, the barrels being thus caused to slide backward upon the tube C and portion B' of the stock, until their rear ends are brought close up to the face of the breech-piece.

When thus closed, the barrels are locked by the spring-catch k of the lever G, as before described, and the strikers s are in contact with the capped nipples q of each of the cartridge-cases. The charges contained in each of the latter are ignited by means of these striker-pins, the outer ends of which are struck by the hammers X of the fire-arm. (See fig. 1.)

After discharging one or both of the barrels, the hooked end of the spring-catch k is, by means of its

ring *k*, disengaged from the notch of the rib *E*, after which it is drawn downward and backward, so as to turn the lever *G* in the direction of the arrow, fig. 1, until the latter assumes its original position, fig. 2, or until the breech is sufficiently opened to permit the removal of the empty cartridge-case or cases, the latter having been withdrawn by the spring extractors *t*, as the barrels were moved forward.

After withdrawing the empty cases, loaded ones may be inserted, and the barrels closed and locked, as before, this operation being repeated as required, while using the arm as a breech-loader.

If the arm is to be used as a muzzle-loader, a cartridge-case is inserted into the rear of each barrel, and, if loaded, may be discharged, as before described.

When the barrels are thus closed, to be loaded from the muzzle, the operating-levers are concealed within the stock, and, with the exception of the ring *k*, the arm presents, externally, the appearance of an ordinary muzzle-loading fowling-piece, while the chambers *p* of the cartridge-cases, forming a continuation of the interior of the bores, can receive the charge inserted at the muzzle.

The tube *C* serves as a sheath for the inner end of the ramrod *L*, by which the barrels are loaded from the muzzle in the usual manner, and after thus loading the barrels, they are opened at the breech, to the

limited extent necessary for placing the caps on the nipples.

Although I have described my invention as applied to a double-barrelled fowling-piece, it will be evident that it may be adapted to fire-arms of other descriptions, the great advantage gained by its use being the fact that no expensive prepared ammunition is required, whether the arm be loaded from the muzzle or the breech, while the devices for opening and closing the breech are of so simple a character that they can be applied to most of the muzzle-loaders in common use.

I claim as my invention, and desire to secure by Letters Patent—

The arm *F*, hinged to the breech-piece, and the operating-lever *G*, jointed, near its centre, to the said arm, and at its end to the barrels, the several parts being arranged so that the barrels shall be moved forward on the backward movement of the operating-lever, as set forth.

In testimony whereof, I have signed my name to this specification, in the presence of two subscribing witnesses.

WILLIAM BRIGGS.
